UNITED STATES PATENT OFFICE

JOHN C. SCHELLENG, OF MILLBURN, NEW JERSEY, ASSIGNOR, BY MESNE ASSIGNMENTS, TO WESTERN ELECTRIC COMPANY, INCORPORATED, A CORPORATION OF NEW YORK

SIGNALING SYSTEM

Application filed May 13, 1925. Serial No. 29,900.

This invention relates to signaling systems and more particularly to short wave transmission apparatus.

In short wave transmitting apparatus, particularly at high power, difficulty is frequently experienced in maintaining the frequency constant due to the high order of frequencies employed. In apparatus of this kind spurious oscillations of high frequency frequently occur due to the inductance of the leads and the capacity of the leads and other apparatus.

It is an object of this invention to provide a high power, short wave radio transmitting apparatus capable of operating at substantially constant frequency.

Another object of this invention is to provide a system of the character described adapted to operate relatively free from spurious oscillations.

These objects and others which will be apparent as the nature of the invention is disclosed are accomplished by selecting a wave of the frequency to be radiated and modulating it in accordance with waves or impulses of signal or control frequency to produce a modulated high frequency current of comparatively low power which is then amplified in successive stages and radiated.

In order to amplify oscillations of high frequency to a power level necessary for transmission over long distances, it is advisable to employ apparatus having leads as short as possible and apparatus in which the deleterious capacity effects are minimized. This is accomplished in a high power amplifier constructed in accordance with the present invention by employing a plurality of stages of amplification, each stage consisting of water-cooled space discharge tubes connected in push-pull relationship.

In order to avoid coupling between the input and output circuits and between the grid and cathode circuits of these tubes and to avoid breakdown due to capacity current flowing in the insulating portions of the tube at high frequencies, a special type of tube is used in which the cathode leads are taken from one end of the tube and the

grid lead from the opposite end. The anode lead is taken through the water jacket at the center of the tube. As tubes operating in push-pull relationship must have their anodes at different instantaneous potentials, it is necessary to connect the water jacket to the circulating water system through insulating connections. 55

In order to avoid any spurious oscillations that might otherwise occur with the tubes operating in push-pull relationship, balancing condensers are connected between the grid of each tube and the plate of the other tube comprising a push-pull amplifier whereby coupling due to the inherent capacity of the tubes is minimized. 60 65

With the tubes connected in push-pull relation, spurious oscillations may be generated, since the tubes so connected have a parallel relationship as regards the generation of oscillations. To eliminate these undesired or spurious oscillations a series of networks are employed connected between the grid and filament and plate and filament respectively of the tubes in such manner 70 75 that a negligible impedance is presented to spurious oscillations in the grid-filament circuit and a high impedance is presented for these oscillations in the plate-filament circuit. Either type of network will serve to 80 prevent oscillations of undesired frequency as oscillations will not be produced provided a low impedance path is inserted between the grid and filament of the tube so that the potential of the grids is prevented 85 from building up at that frequency, or oscillations will not be produced provided a sufficiently high impedance path is presented at that particular frequency between the anode and filament. 90

In order to simplify the mechanical construction and the wiring of the above apparatus and to improve the operating characteristics, the entire assembly is arranged symmetrically with respect to a vertical plane extending from the input end of the apparatus to the radiating system. Such an arrangement prevents, to a large extent, unbalanced electrical constants of the circuit. A push-pull arrangement is preferred 100

for the reason that a neutral lead is provided in which impedance or other changes may be made without affecting the operation of the circuit as a push-pull repeater.

5 Although the novel features which are believed to be characteristic of this invention will be pointed out with particularity in the claims appended hereto, the invention itself, as to objects and advantages, the mode of its 10 operation, and the manner of its organization will be better understood by referring to the following description taken in connection with the accompanying drawing forming a part thereof in which:

15 Fig. 1 is a diagrammatic representation of a simplified form of this invention.

Fig. 2 shows schematically a transmission circuit constructed in accordance with this invention.

20 Fig. 3 is an elevation, partly in section, of an amplifier unit used in the system shown in Fig. 2.

Fig. 4 is a plan view of the amplifier unit shown in Fig. 3.

25 In Fig. 1 is shown a push-pull amplifier comprising space discharge tubes 25 having input and output circuits connected to transformers 23 and 24 respectively. Reactance coil 28, connected across the grids of tubes 25, together with condenser 29 and resistance 30, which connects the center portion 30 of reactance 28 to ground, tend to suppress undesired oscillations which occur with the tubes operating in effective parallel relationship especially at high frequencies. Condenser 29 is of such value that the circuit, including the parallel opposing reactances 35 of the two halves of the coil 28 which cooperate with condenser 29 to form a shunt 40 to the grid filament circuit of the tubes, is tuned to the frequency at which the spurious or undesired oscillations occur. In a particular installation, this frequency was found to be of the order of 10,000 kilocycles.

45 Resistance 30 introduces a damping impedance to these oscillations which tends to prevent their building up, or causes them to be dissipated as heat. The lead including condenser 29 being at the same potential as the 50 common filament connection of the tubes for oscillations occurring with the tubes operating in push-pull relationship, no current will tend to flow through this lead during normal operation. For oscillations which occur

55 with the tubes operating as generators in parallel, however, the path including the condenser 29 and resistance 30 will have the entire grid filament potential impressed across them and will act as a dissipating 60 path as above set forth.

A certain type of oscillations, occurring with the tubes operating in push-pull relationship due to the output circuit of the amplifier reacting upon the input circuit 65 through coupling due to the inherent capac-

ity of the tubes, is prevented by balancing condensers 26 connected between the grid of each tube and the anode of the other tube comprising the push-pull amplifier. Choke coil 27, in the common plate circuit of the 70 tubes, lowers the frequency at which certain oscillations tend to occur in this circuit with the tubes operating in parallel relationship to a point below the frequency of the waves to be amplified and offers a high impedance 75 to spurious oscillations.

In the system shown in Fig. 2, rectangle 1 is used to represent a source of modulated high frequency oscillations comprising either one or both modulated components with or without the unmodulated component which may be of the order of 2,000 to 6,000 kilocycles. Modulated high frequency current from this source is impressed upon amplifier 2 including tubes 25 constituting a stage of 85 push-pull amplification through transformer 23. The secondary of transformer 23 is tuned by means of condensers 22 to the operating frequency. The high frequency path between the grid and filament is completed by the ground connection 21 at the midpoint of condensers 22. Grid polarizing potential is applied to tubes 25 from source 10 through potentiometers 11 and 12 by means of which the potential applied 90 to the grids of the tubes may be independently adjusted. Filter 13 is designed to suppress high frequency or other fluctuating components of the grid polarizing potential which might be generated by the source 10, 100 or any high frequency currents which might be picked up by the leads from generator 10. Choke coils 14 are used to prevent high frequency current from the grid-filament circuit from being impressed upon source 10. Condensers 15 serve as stopping condensers 105 to enable the grids to be separately adjusted. Coils 16 are tuned by condenser 17 to the frequency of any spurious oscillations 110 which might tend to occur and which are conducted through condenser 17 and resistance 18 to ground, in a manner similar to that described in connection with condenser 29 and resistance 30 in the system shown in Fig. 1. Balancing condensers 19 are connected between the grids and anodes of tubes 115 25 in a manner similar to condensers 26 of Fig. 1.

Filament heating current is supplied to the tubes from source 31 through transformers 32 and 33, respectively. Filters 34 and 35 are designed to prevent high frequency currents from being impressed upon the transformers and source 31 from the operating 120 circuits.

Anode potential is supplied to tubes 25 from source 40 through filter 41 and coils 42 and 43 which are designed to offer a high impedance to high frequency currents. A direct current path for the anode current of 130

the tubes is secured to the filament through filter 44 which is designed to prevent any high frequency currents which might be present in the anode leads from being applied to the secondaries of the transformers 32 and 33. The transformers are further protected by safety gaps 45 and choke coils 46 which are included in the connections between the secondaries of transformers 32 and 33 and ground. The safety gaps also prevent destructive arcs being formed should a break occur in the leads.

10 Energy is transferred between amplifier 2 comprising tubes 25 and associated circuits and amplifier 3 which is similar in all respects to the above described stage of amplification by means of tuned coupling circuit 50 comprising transformers 51 and 52 and variable condenser 53 by means of which the 15 secondary of transformers 51 and 52 are tuned to the desired operating frequency.

15 The primary windings of transformers 51 and 52 are connected to ground 55 to allow any charge that may accumulate upon the 20 coils due to leakage of current from source 40 through condensers 56 to be conducted to ground. Choke coil 54 in the ground lead offers a high impedance path for spurious 25 oscillations which would tend to occur were a low impedance path provided to ground. The use of the choke coil is necessitated by the ground connection. The secondary windings of transformers 51 and 52 are connected to ground 57 to provide a high frequency 30 path between the grid and cathode of the tubes comprising amplifier 3. Blocking condensers 58 are used to permit the direct current potential of the grids to be separately 35 adjusted.

40 Amplifier 3 contains apparatus similar to that shown for amplifier 2 connected in a similar manner and is coupled to an antenna or radiating circuit 60 by means of transformers 61 and 62 comprising, in connection with condenser 63, a tuned coupling circuit. Anode potential is applied to the space discharge devices of amplifier 3 from source 64 through filter 65 and variable inductances 66 and 67 which are tuned by means of condenser 68 to the operating frequency. Ground lead 57 and choke coil 69 are for the same purpose in amplifier 3 as ground lead 55 and choke coil 54 in amplifier 2. Choke coil 59 in the lead to the space current source 64 is used to prevent a certain low frequency type of oscillation which was noted in a system operative without this coil. The overhanging turns of coils 66 and 67, that is, the turns not included in the circuit between the terminals of condenser 68, have been found to materially assist in preventing spurious high frequency oscillations and to stabilize the system although no definite theory has been developed to explain these operations.

45 In the operation of this system, oscilla-

tions are prevented from occurring with the tubes operating in effective parallel relationship by means of coils 16 which are tuned by condenser 17 to be of low impedance to oscillations of this kind. This tends to prevent potential building up between the grids and the filaments of the space discharge devices which will tend to force oscillations through the circuit. Certain oscillations which do tend to occur, however, are suppressed by various high impedance paths between the plates and filaments of the tubes such as that presented by coils 54, 42, 43, 69, 59 and the overhanging turns of coils 66 and 67. Spurious oscillations of the push-pull type are prevented by balancing condensers 19, except at very high frequencies where the inductive reactance of the loop circuit, comprising condensers 19, the internal capacities of tubes 25 and the leads, become large. Spurious oscillations of the order of 30,000 kilocycles were noted under some circumstances and were eliminated by making the inductances of the loop negligible. This was done by reducing the area of the loop, making the leads short and increasing the diameter of the leads.

50 Figs. 3 and 4 disclose the physical arrangement and construction of the elements of one of the amplifier units of Fig. 2. In Figs. 3 and 4 the space discharge tubes 25 have grid connections 71 extending through the glass portions 72 at the top of the tubes and filament connections 73 entering through glass portions 74 at the lower end of the tubes. Circular anodes 75, including water jackets, 55 provide supporting means for the tubes. Cooling water is supplied to each tube through a rubber hose shown as coil 76 in the lower portion of the container.

55 Each tube 25 is supported by means of insulators 77 and 78 connecting the sides of the container 79 with conducting yoke 80 in which anode 75 of the tube is clamped. Balancing condensers 19 are supported from the anode connections of the tube by means of brackets 81. The anode connections of the tube are taken by means of lead 82 from bracket 80 through the side wall of the container 79 from which it is separated by insulator 83. Coil 16, condensers 15 and 17, and resistance 18 are supported at the top portion of the unit. Condensers 37 and 39 and inductances 38 comprise filters 34 and 35 of Fig. 2. A filament supply transformer 33 for each tube is placed below shield 70 which prevents currents being induced from the operating high frequency apparatus into the transformer or other apparatus below shield 70.

60 In constructing each amplifier stage and the circuit as a whole, it is found advisable to arrange all the parts substantially symmetrically with respect to a vertical plane traversing the entire assembly in order that

leads to the various tubes may be of the same length, and to better enable the circuit to be maintained in a balanced condition.

In short wave transmission systems of high power it has been found that undesired oscillations of various types tend to occur. Means tending to prevent the occurrence of each type of possible oscillation must be employed in such a manner as to not interfere with the prevention of oscillations of another type. In the circuit herein described the theoretical explanation of the operation of each and every element can not be given. However, it appears that symmetry of design tends to prevent those oscillations which might result from an unbalanced circuit. One type of oscillation which occurs with the tubes operating in push-pull relationship is prevented by the use of the condensers 19 and another type which occurs with the tubes operating in parallel relationship is prevented by the combined effects of condenser 17, resistance 18 and coils 16. The overhanging turns of coils 66 and 67 have an additional effect in preventing undesired oscillations. Coils 42 and 43 and coil 59 prevent oscillations of a frequency lower than the operating frequency which tends to occur in the circuit and coils 54 and 69 prevent oscillations which would occur if a low impedance path to ground were provided.

This system was found to be free from spurious oscillations when the foregoing precautions were taken after a rigid test comprising applying full anode potential to the tubes and reducing the negative grid polarization to zero while no signals were impressed upon the amplifiers from source 1. In this condition high plate currents flow in the circuit which would tend to produce spurious oscillations were they not prevented from occurring. Before the various means above described were employed to completely prevent undesired oscillations during operations at full power, spurious oscillations occurred of sufficient power to melt the glass of the tubes and of the condensers by heating the leads.

In a particular instance, the following values have been found desirable for certain elements. Coils 16 have a series aiding inductance of 20 microhenries as measured from grid to grid of the tubes 25. Variable condenser 17 has a maximum capacity of 200 micromicrofarads. Resistance 18 is of the order of 200 ohms. Coils 54, 59 and 69 have an inductance of 100 microhenries. Coils 66 and 67 have a total inductance of about 20 microhenries and one or two overhanging turns. Condenser 68 has a maximum capacity of 150 micromicrofarads. The electrical constants of the other elements may be determined in accordance with known principles.

Although this invention has been described as applied to a particular system it is not to be limited thereto but only in accordance with the scope of the invention as defined by the following claims.

70

What is claimed is:

1. A high power transmission system including a source of high frequency waves and an amplifier therefor comprising a plurality of space discharge devices for use at such high frequency that parasitic oscillations tend to occur characterized in this, that the devices are connected in opposed relation with respect to the source of waves and that a dissipative path is provided for the parasitic oscillations whereby they are substantially suppressed.

75

2. A system in accordance with claim 1, characterized in this, that the dissipative path consists of a high impedance for parasitic oscillations connected between the grid electrodes of the pair of devices arranged in opposed relation with respect to the source of waves and a low impedance path for said oscillations between the mid-portion of said high impedance and the ground connections or grounded cathode elements of said devices.

85

3. A high power transmission system including a source of high frequency waves and an amplifier therefor comprising a plurality of space discharge devices for use at such high frequency that parasitic oscillations tend to occur, said devices being connected in opposed relation with respect to the source of waves, and a dissipative path for the parasitic oscillations whereby they are substantially suppressed, said dissipative path consisting of a high impedance for parasitic oscillations connected between the grid electrodes of the pair of devices arranged in opposed relation with respect to the source of waves, and a low impedance path for said oscillations between the mid-portion of said high impedance and the ground connections or grounded cathode elements of said devices, said low impedance path comprising a condenser and resistance in series.

95

4. A system in accordance with claim 1, characterized in this, that the dissipative path consists of impedance elements so arranged and adjusted that potentials of undesired or spurious character are prevented from building up, whereby oscillations due to either the push-pull or parallel relation of the tubes are prevented.

5. A system in accordance with claim 1, characterized in this, that the dissipative path comprises a low impedance for parasitic oscillations in the input circuits of the devices whereby potentials are prevented from building up and a high impedance for said oscillations in the output circuit of the

devices whereby any oscillations that tend to occur are suppressed.

6. A high power transmission system including a source of high frequency waves and an amplifier therefor comprising a plurality of space discharge devices for use at such high frequency that parasitic oscillations tend to occur, said devices being connected in opposed relation with respect to the source of waves, and a dissipative path for the parasitic oscillations whereby they are substantially suppressed, said dissipative path consisting of a high impedance for parasitic oscillations connected between the grid electrodes of the pair of devices arranged in opposed relation with respect to the source of waves, and a low impedance path for said oscillations between the mid portion of said high impedance and the ground connections or grounded cathode elements of said devices, and balancing condensers connected between the grid of each device and the anode of the other device comprising the push-pull amplifier, cooperating with said dissipative path whereby coupling between the input and output circuits due to inherent capacity of the devices is avoided.

7. In a signaling system, a source of high frequency signal modulated waves, means for amplifying said waves comprising a plurality of space discharge devices arranged in push-pull relationship, and a low impedance path between the grid and the cathode of said devices for dissipating undesired oscillations.

8. In a signaling system, a source of high frequency signal modulated waves, means for amplifying said waves comprising a plurality of water-cooled space discharge devices arranged in push-pull relationship, and means comprising electrostatic shields for preventing undesired oscillations in said system.

9. In a signaling system, a source of high frequency signal modulated waves, means for amplifying said waves comprising a plurality of space discharge devices arranged in push-pull relationship, and means comprising an electrostatic shield surrounding said amplifier and a low impedance path between the grid and the cathode of said tubes for preventing undesired oscillations.

10. In a high power short wave radio signaling system, a source of high frequency signal modulated waves, means for amplifying said waves comprising a plurality of stages, each stage consisting of two space discharge tubes connected in push-pull relationship, a cathode connection being at one end of said tubes and a grid connection at the other end of said tubes, balancing condensers for preventing electrostatic coupling between the input and output circuits of said tubes due to the internal capacity thereof, an electrostatic shield surrounding

each of said stages of amplification, means for preventing spurious oscillations in said system comprising a low impedance path for said oscillations between the grid and filament of said tubes and a high impedance path for said oscillations between the anode and filament of said tubes.

11. In a high power short wave transmitting apparatus comprising a plurality of stages of amplification, each stage comprising a pair of space discharge tubes, means for preventing undesired oscillations in said system comprising a high impedance path for said oscillations between said tubes and a low impedance path for said oscillations between each of said tubes and ground.

12. In a high power short wave transmitting apparatus comprising a plurality of stages of amplification, each stage comprising a pair of space discharge tubes, means for preventing undesired oscillations in said system comprising a high impedance for said oscillations connecting the grids of each pair of tubes, and a low impedance path comprising a condenser and resistance in series connecting the mid-point of said impedance and ground.

13. In a high power short wave radio transmitting system a plurality of stages of amplification, each stage comprising a pair of water cooled space discharge tubes arranged in push-pull relationship said tubes having anodes, cathodes and control electrodes, cathode connections at one end of said tubes, control electrode connections at the other end of said tubes, a water jacket surrounding the anodes of said tubes, means for mounting said tubes comprising a yoke adapted to clamp said water jacket, and supporting means for said yoke comprising a pair of insulating compression members arranged at an acute angle to the vertical whereby the bending moment of said members is reduced.

14. In an amplifier comprising a pair of space discharge tubes arranged in push-pull relationship, means for dissipating parasitic oscillations caused by said tubes operating in parallel comprising a low impedance path for said oscillations between a point of neutral potential for push-pull oscillations and ground.

15. In a push-pull amplifier comprising a pair of three-electrode space discharge devices, means for preventing parasitic oscillations caused by said tubes operating in parallel relationship comprising a high impedance path for oscillations occurring in parallel operation and a low impedance path for oscillations occurring in push-pull operation.

In witness whereof, I hereunto subscribe my name this 7 day of May A. D. 1925.

JOHN C. SCHELLENG.
